UNITED STATES PATENT OFFICE.

OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

YIELDABLE GIVEWAY FOR WEFT-REPLENISHING LOOMS.

Application filed November 15, 1926. Serial No. 148,404.

This invention relates to improvements in weft replenishing looms more particularly of the multi-color type, and it is the general object of the invention to provide a yieldable support more particularly for the tips of bobbins as the latter await transfer.

In weft replenishing looms of the multi-color type the bobbins are arranged in parallel vertical stacks according to distinctive characteristics and are released at the proper time to move to a common transfer position centrally located under the stacks. When in this position the bobbins are held by yieldable supports which move slightly at the time of transfer to permit the new bobbin to pass into the exhausted shuttle. It is an important object of my present invention to provide a very simple bobbin support which is suspended from a comparatively high point in the replenishing mechanism but is accurately placed by means of a locating lug near the bottom of the mechanism so that the end of the support may be accurately placed.

It is a further object of my invention to provide a yieldable support of wire, a portion of which is wound on itself to afford a coil to permit yielding movement thereof.

Occasionally a bobbin is not properly transferred and will stick upwardly from the shuttle as the lay moves backwardly. Under such conditions the misplaced bobbin is likely to engage the supports and carry the same rearwardly. In order to prevent breakage under such conditions it has been necessary heretofore to construct rather elaborate giveways or supports and it is a further object of my present invention to provide means for requiring the support to move longitudinally away from the bobbin under the conditions just mentioned so that the bobbin may be free to move off the support without undue movement of the latter or to move rearwardly without distorting or fracturing the support.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a vertical section through a multi-color magazine having my invention applied thereto,

Fig. 2 is a rear elevation of a portion of the magazine taken in the direction of arrow 2, Fig. 1,

Fig. 3 is an enlarged detail top plan view taken in the direction of arrow 3, Fig. 1,

Fig. 4 is an enlarged rear elevation of parts shown in Fig. 1 taken in the direction of arrow 4 of said figure,

Fig. 5 is an enlarged horizontal section on line 5—5 of Fig. 1, and

Fig. 6 is an end elevation of the bobbin and portions of the support taken in the direction of arrow 6, Fig. 4.

Referring to the drawings it will be seen that I have provided a multi-color magazine frame 10 having a series of vertical compartments 11 in which are located bobbins W, said bobbins being arranged in the compartments according to color or other distinguishing characteristic. In the bottom of the magazine are located a series of so-called cradles 12, one for each of the stacks, and said cradles are oscillated about their horizontal axes, one at a time, by mechanism not shown, to move a bobbin toward transfer position. Ordinarily the bobbins of any one stack will be located above the corresponding cradle, the latter being empty, and at the time of indication of weft exhaustion the proper cradle will rock so that the lowermost bobbin of the associated stack can move downwardly into the cradle. On a subsequent pick when the indicating shuttle returns under the magazine the cradle will be rocked back to normal position, thus releasing the lowermost bobbin. At this time the bobbin which has been freed by the cradle will move downwardly on inclined runs and roll to a position centrally located under the stacks immediately above the shuttle when the lay is in its extreme forward position. A transerrer arm indicated in section at 13 will then descend to insert a bobbin into the shuttle S.

Vertical thread slots 15 are located as shown in Fig. 1, the lower portions being oblique and defined in part by surface 16 on the outer part of the frame and in part by surface 17 formed on the inner portion of the magazine. Runs 18 connect with the

walls of the outer stacks and define surfaces along which the tips of the bobbins may roll toward transfer position. The matter thus far described, except the reference to 5 the inclined supports, is old and may be substantially as shown in patent to Ryon No. 1,030,748. Reference to said patent will show that the magazine or replenishing mechanism is formed of two spaced parallel 10 vertical plates between which the bobbins lie, said plates being held together by tie rods 14.

In carrying my invention into effect I provide a pair of giveways for the tip of 15 the bobbin. The rear giveway 20 is formed of wire and has an upwardly extending arm which is wound with several coils 21 which lie around a sleeve 22 formed on a collar 23 located on the rear upper tie rod 14. By 20 means of a set screw 24 said collar can be held in adjusted angular position on the tie rod so as to vary the pressure of the wire giveway 20.

The forward giveway 30 is formed of another piece of wire and has the upper end 25 thereof formed similarly to the upper end of the first described support, being held on a collar 31 which is secured in adjusted position to the lower front tie rod 14. The 30 upper free end of each of the wire giveways or supports is bent to extend substantially parallel to the associated tie rod and is received in a recess 32 in the corresponding collar.

35 The lower ends of the supports are substantially the same and a description of one will suffice for both. As shown in Fig. 1 the lower end of giveway 20 has a horizontal extension 40 on which is secured a 40 stop 41 held in longitudinal position on the horizontal portion 40 by means of screw 42. Said collar may be formed as shown in Fig. 4 and has a diagonal slot 43 oblique with respect to the axis of the screw 42 so that the 45 latter together with the slot will prevent movement of the support out of said slot and thus insure proper positioning of the stop collar 41. The latter is formed with a V-shaped end 44 which is received in a corresponding notch 45 located in an extension 46 of the magazine frame 10. Beyond the horizontal portion 40 the wire support is inclined downwardly and forwardly as at 50 and is bent outwardly away from the center 55 of the magazine as at 51 to define a supporting portion for the tip of the bobbin and is then bent upwardly as at 52. The free end of the wire is then extended upwardly and rearwardly as at 53 substantially parallel to the portion 50 to prevent endwise movement of the bobbin by engagement of the tip thereof. Undue movement of the support 20 outwardly in a direction parallel to the axes of the bobbins may be prevented 60 by lug 54 forming a usual part of the maga- 65

zine frame and undue movement in the opposite direction is prevented by the extension 46.

The upper and rearwardly extending end 53 is bent outwardly as shown at 55 in 70 Fig. 3 and a portion of the magazine frame 10 is provided with an inclined face 56 to cooperate with the end 55 to move the support in a direction lengthwise of the bobbin when for any reason said support is moved 75 rearwardly an undue distance by a misplaced bobbin. The forward giveway 30 is substantially the same as the rear giveway 20 except that the vertical portion thereof is shorter. 80

During the operation of transferring one or both of the wire supports will yield slightly away from the axis of the bobbin, the wedge-shaped collar 41 moving away from the notch 45. As soon as the bobbin 85 is below the supports the coiled portions thereof will move the supports back to normal position, the wedge-shaped ends 44 of the collar entering the notches to locate the portions 50 and 53 correctly. Adjustment of 90 the bobbin engaging ends of the supports with respect to the axis of the bobbin in transfer position can be effected by means of the screws 42.

From the foregoing it will be seen that 95 I have provided a pair of very simple yielding bobbin supports the upper ends of which are coiled to afford the necessary resilience and the lower ends of which are inclined and bent back so that a portion thereof lies 100 above and beyond the guide portion to prevent endwise motion of the bobbin. Furthermore, it will be seen that the collars 41 cooperate with the notches 45 to correct the position of the supports after a transfer. It 105 will also be seen that by reason of the inclined face 56 and the bent end 55 the lower end of the rear support 20 may be caused to move in a direction parallel to the bobbins in order to clear itself of an improperly placed bobbin. 110

Having thus described my invention it will be apparent that changes and modifications may be made therein by those skilled in the art without departing from the spirit 115 and scope of the invention, and I do not wish to be limited to the details herein disclosed but what I claim is:

1. In a weft replenishing mechanism having a frame to hold a plurality of stacks of bobbins, a pair of yieldable supports for the tip of the bobbin, one of said supports being formed of wire bent on itself and having two inclined portions spaced vertically and horizontally, the upper portion to engage 120 the tip of the bobbin and prevent endwise movement thereof and the lower portion guiding the bobbin toward and supporting the same in transfer position. 125

2. In a weft replenishing mechanism hav- 130

ing a frame to hold a plurality of stacks of bobbins, a pair of yieldable supports for the tip of the bobbin, one of said supports being formed of wire bent on itself and having two inclined portions spaced vertically and horizontally, the upper portion to engage the tip of the bobbin and prevent endwise movement thereof and the lower portion guiding the bobbin toward and supporting the same in transfer position, said portions being connected by a substantially horizontal part of the wire adapted to have the tip of the bobbin rest thereon.

3. In a weft replenishing mechanism having a frame to hold a plurality of stacks of bobbins, means to support the front of the tip of a bobbin in transfer position, a yieldable support for the back of the tip of the bobbin in transfer position, said support formed of wire the upper end of which is held to the replenishing mechanism frame and the lower portion of which is formed to guide a bobbin toward and hold the same in transfer position, and means carried by the said wire to engage a notch formed in the frame to position the bobbin supporting end of said wire support.

4. In a weft replenishing mechanism having a frame to hold a plurality of stacks of bobbins, a pair of yieldable bobbin supports for the tip of the bobbin, one of said supports formed of wire and having the lower end thereof inclined to guide the tip of the bobbin toward and support the same in transfer position, the upper end of the wire being secured to the frame, said support being resilient and held by its own resilience in bobbin supporting position and movable therefrom under action of a bobbin, and positioning means carried by said wire support to engage a notch in the frame to position the bobbin engaging portion of said wire support both horizontally and vertically.

5. In a weft replenishing mechanism hav-

ing a frame to hold a plurality of stacks of bobbins, a pair of bobbin supports to hold the tip of a bobbin in transfer position, one of said supports being formed of wire and having the upper end thereof coiled and held in position relatively to the frame, the lower end of the wire being inclined downwardly and toward transfer position to guide the tip of a bobbin toward and support the same in transfer position, and means intermediate the ends of the wire and rigid with respect thereto to enter a notch formed in the frame to position the tip supporting end of the wire vertically and horizontally.

6. In a weft replenishing mechanism having a frame to hold a plurality of stacks of bobbins, means defining an inclined surface on the frame extending rearwardly and outwardly with respect to a bobbin in transfer position, and a yielding support for the rear of the tip of a bobbin in transfer position to engage said inclined means, said support when moved rearwardly by an improperly placed bobbin engaging the inclined means to move in a direction longitudinally away from the bobbin, whereby said support will move from under the tip of the bobbin.

7. In a weft replenishing mechanism having a frame to hold a plurality of stacks of bobbins, a pair of supports for the tip of a bobbin, one of said supports being formed of wire, and a positioning device rigid with respect to the wire support and having an open slot therein for the reception of the wire, and means extending through said device and engaging the wire to hold the device and wire in fixed position relatively to each other, said slot extending in such a direction as to have a component thereof parallel to the securing means.

In testimony whereof I have hereunto affixed my signature.

OSCAR V. PAYNE.
